TYPEWRITING AND LIKE MACHINE

Henry A. Heinrich, Middletown, Conn., assignor
to Remington Rand Inc., Buffalo, N. Y., a cor-
poration of Delaware

Application December 5, 1938, Serial No. 243,976

17 Claims. (Cl. 197—136)

My invention relates to typewriting and like machines, and more particularly to improved means for clamping cards or the like to the platen of such machines.

5 The main object of my invention, generally stated, is to provide improved, highly efficient and reliable card clamping means for typewriting and like machines whereby a card or like article may be fed either forward or backward with the platen as may be desired.

10 A more specific object of my invention is to provide improved card clamping means of the character specified which are operated automatically during the rotation of the platen for opening and closing the card clamp at given points in such rotation whether a forward or backward feed of the card is being effected.

To the above and other ends which will herein-after appear, my invention consists in the features of construction, arrangements of parts and combinations of devices set forth in the following description and particularly pointed out in the appended claims.

15 In the drawings, wherein like reference characters designate corresponding parts in the different views:

20 Fig. 1 is a fragmentary front elevation view of a platen and associated parts of a No. 10 Remington Noiseless Typewriting Machine equipped with the devices of my invention.

25 Fig. 2 is an enlarged, fragmentary, longitudinal sectional view of the platen and certain associated parts shown in Fig. 1, the section being taken on the line 2—2 of Fig. 6 and viewed in the direction of the arrows at said line.

30 Fig. 3 is an enlarged transverse sectional view of the same taken on line 3—3 of Fig. 1 and viewed in the direction of the arrows at said line, the card clamp being shown in the released position.

35 Fig. 4 is a view similar to Fig. 3 but showing various parts as they appeared at a different rotated position of the platen and with the card clamp closed.

40 Fig. 5 is an enlarged transverse sectional view taken on line 5—5 of Fig. 1 viewed in the direction of the arrows at said line; the parts being shown as they appear at the rotated position of the platen shown in Fig. 3.

45 Fig. 6 is an enlarged transverse sectional view taken on line 6—6 of Fig. 1 and viewed in the direction of the arrows at said line; the parts also being shown as they appear at the rotated position of the platen shown in Fig. 3.

50 Fig. 7 is a view similar to Fig. 6 but showing

certain parts as they appear at the rotated position of the platen shown in Fig. 4.

5 Fig. 8 is another view similar to Fig. 6 but showing certain parts as they appear at still a different position of rotation of the platen.

I have shown my invention embodied in the present instance in a No. 10 Remington Noiseless machine in which the features of the present invention may be readily incorporated with but few changes in the existing structure. However, it is to be understood that my invention is not restricted to embodiment in such machine, but may be employed in various other types of typewriting and like machines wherever found available.

10 I have shown in the drawings only so much of the usual construction of the No. 10 Remington Noiseless machine as is necessary to arrive at an understanding of my invention and its embodiment therein.

15 The platen shown in the accompanying drawings is generally the type employed in the No. 10 Remington Noiseless machine, and as may be seen in Fig. 2 the platen includes a metal shell 10 which has permanently secured thereto at its left hand end a platen head 11 having a concentric platen shaft section or trunnion 12. This platen shaft may be of the usual construction adapted to be detachably mounted in the usual manner for rotation in the left hand carriage end 20 plate of the machine. A similar platen head 14 is secured to the right hand end of the platen shell 10 by several spaced screws 15, one of which is shown in Fig. 2. The platen head 14 is provided with a concentric platen shaft section or 25 trunnion 16 which carries a bearing bushing 17 that enables the platen to be detachably mounted in the usual manner for rotation in the right hand carriage end plate 18. A finger piece or twirler 19 may be provided having an inwardly 30 extending hub portion 20 threaded on the extending end of the platen trunnion 16. A covering 24 of suitable rubber composition is attached in the usual manner to the outer surface of the metal shell 10.

35 The usual paper feeding means may be employed to coat with the platen, which has been shown in Fig. 1 and Fig. 3, for example, as including front feed rollers 26 and back feed rollers 28 and paper apron 30, all of which are 40 mounted on the usual mechanism whereby they are spring pressed toward the platen to hold a work sheet or the like in contact with the platen covering 24. The feed rollers 26 and 28 extend through respective openings in a curved paper 45 50 55

apron 38 extending beneath and in the rear of the platen in the usual manner.

The features thus far described are, or may be, of the usual construction.

5 The card clamping means of the present invention includes a clamping member in the form of metal strip 34, preferably extending longitudinally substantially throughout the length of the platen. The member 34 coacts with a recessed or flattened portion 35 on the surface of the platen which extends longitudinally of the platen substantially throughout the length thereof. The clamp 34 may be provided with an inwardly turned portion 34^a (see Fig. 2) at its left-hand end, said portion 34^a registering with an opening 34^b in the flattened portion 35 of the platen covering 24, which portion 34^a may serve as a guide for the side edge of a card.

20 A series of spaced plungers 36 extend radially from the interior of the platen through companion openings in the shell 10 and cover 24. The outer end of each of the plungers 36 is attached by a screw 37 to the clamp 34 along a central line thereof so as to leave an overlapping portion along both sides of the clamp and beneath either of which overlapping sides of the clamp an edge portion of a card may be received, as shown in Figs. 3 and 8. A reduced inner end portion 36^a of each of the plungers 36 passes 25 through a companion opening in a connecting bar 38, and the portion 36^a may be riveted thereto as shown in Figs. 2 and 3. The bar 38 extends longitudinally within the platen about the length of the clamp 34 and thus serves to securely 30 join the inner ends of all the plungers 36.

35 A compression spring 40 extends between each end portion of the bar 38 and the opposite inner wall of the shell 10. The inner end of each of the springs 40 surrounds a companion pin 41 secured to the bar 38 to prevent lateral displacement of the spring. The force of the springs 40 on the bar 38 thus acts through the plungers 36 to move the clamp 34 to and resiliently hold it in an outward or open released position.

40 The means for closing the clamp 34 includes a rock shaft 45 extending longitudinally of the platen within the shell 10 and passing through an opening 46 provided in the central portion of each of the plungers 36. As may be seen 45 in Fig. 2, the left hand end of the rock shaft 45 is rotatively supported and guided in a bearing slot or opening 48 in the left hand platen head 11. The right hand end of the rock shaft 45 passes through a bearing slot or opening 49 in right hand platen head 14. As may be seen in Fig. 3 and Fig. 4, a cam surface is formed along the rock shaft 45 by a flat side 45^a extending longitudinally thereof and substantially throughout its length. It may also be seen that the 50 opening 46 in each of the plungers 36 is provided with a flat end wall 46^a, and when the rock shaft 45 is turned from the position shown in Fig. 4 to that shown in Fig. 3, this straight end wall portion 46^a is held in engagement with the flat side 45^a of the rock shaft by the force of the springs 40 thus holding the card clamp in the released position by the force of said 55 springs.

60 In order to support the rock shaft 45 against the outward force of the springs 40 acting thereon through the plungers 36, a sleeve 47 is provided around each of the plungers 36. Each of these sleeves 47 may be slotted as shown in Figs. 3 and 4 to receive the enlarged flat portion of the companion plunger 36 which surrounds the

65 opening 46 therein. Each sleeve 47 extends between the outer surface of the rock shaft 45 and the inner surface of the shell 10 and thereby prevents outward flexing of the intermediate portion of the rock shaft 45 by the force of the 5 springs 40.

70 Referring to Fig. 3, it will be noted that the curved outer end wall of the opening 46 in each of the plungers 36 is spaced outwardly from the curved surface of the rock shaft 45 when the straight wall 46^a is held in engagement with the flat side 45^a of the rock shaft. Thus, when the rock shaft 45 is turned in either direction from the position shown in Fig. 3, one of the edges of the flat side 45^a will exert a camming action 15 against the straight wall portion 46^a to move all of the plungers 36 inwardly against the force of the springs 40 to a position such as that shown in Fig. 4. This inward movement of the plungers 36 positively draws the clamp 34 inwardly to a 20 closed position with relation to the flat surface 35 of the platen covering 24 and against the intervening card to be held by the clamp.

25 Means are provided in accordance with the present invention for automatically turning the rock shaft 45 to open and close the clamp 34 by a rotation of the platen to and from the positions shown in Figs. 3 and 4 respectively for example. This automatically operating means for turning the rock shaft to thereby open and 30 close the clamp are also arranged in accordance with the present invention to open and close the clamp by a rotation of the platen to and from a different position shown in Fig. 8 to facilitate the feeding of a card either backward or forward 35 with the platen as may be desired.

35 The illustrated means for automatically operating the rock shaft 45 in the present instance includes a control finger or arm 50 carried by a portion of the rock shaft which extends outside the platen head 14. An operative connection between the arm 50 and the rock shaft 45 is effected in accordance with the present invention to afford a slight extent of resilient movement of the arm relative to the rock shaft, for 40 purposes which will later be described in detail. This resilient connection is shown particularly in Fig. 2 and Fig. 5 wherein it may be seen that an opening 51 is provided in the arm 50 to receive the end of the rock shaft 45, which opening 45 is shorter than the opening 46 in each of the plungers 36 but otherwise of generally the same shape. An expansion spring 52 extends between the end wall of a centrally disposed opening in the arm 50 and a recessed flattened portion at 55 45^a near the right hand end of the rock shaft 45.

60 As may be seen in Fig. 5, the force of the spring 52 thus acts between the arm 50 and the rock shaft 45 to normally hold a straight wall portion 51^a of the opening in the arm 50 into engaged relation with the flat side 45^a of the rock shaft. The tension of the spring 52 is such that normally a turning movement of the arm 50 will turn the rock shaft 45 and effect an inward movement of the plungers 36 against the force of the spring 65 40 without separating the surfaces 45^a and 51^a. However, when a full extent of inward movement of the clamp 34 cannot be effected due to its engagement with a card, say, of unusual thickness, it will be clear that a continued movement of the 70 arm 50 may be afforded by a pivotal movement thereof about an edge of the flat side 45^a of the rock shaft against the force of the spring 52.

75 The outer rounded end of the finger or arm 50 coacts during rotation of the platen with a 75

fixed circular track formed in the present instance by the inner surface of a flange 54 on a disc 55. The outer surface of the flange 54 may be substantially the same diameter as the platen covering 24, and the disc 55 is provided with a centrally disposed opening receiving the right hand platen trunnion 16. The disc 55 is held in spaced relation to the platen head 14, jointly by the end of the rock shaft 45 and by the end of headed pins 57 extending outwardly from the platen head 14, as shown in Fig. 2 and Fig. 6. The disc 55 is retained against outward displacement on the trunnion 16 by a collar 58 attached at 59 to said trunnion.

15 The disc 55 is held against rotation with the platen by a shouldered pin 60 threaded into the right hand carriage end plate 18 and extending inwardly therefrom into a slot 61 provided in the disc 55, as shown in Fig. 5. The provision of the 20 slot 61 and pin 60 permits a platen provided with the disc 55 to be removed from the carriage as a single unit and yet provides an effective means for retaining the disc against rotation.

As previously stated, the rounded end of the 25 finger or arm 50 coacts with the inner surface of the flange 54, and in order to automatically open and close the clamp 34 at either of two predetermined control positions of rotation of the platen, two openings 64 and 66 are provided at 30 different locations in the flange 54. In Figs. 2, 3, 5 and 6, the end of the arm 50 is shown extending through the opening 64 thereby resulting in a radial position of the arm relative to the platen. This radial position of the arm 50 in turn effects 35 a position of the rock shaft 45 to allow the clamp 34 to be operated to and retained in an open position under the force of the springs 40 as previously described.

At the position of the platen shown in Fig. 3 40 and Fig. 6, the top edge portion of a card 68 may be inserted in the space between the clamp 34 and the flattened portion 35 of the platen so that the edge of the card rests against the sides of the plungers 36. If the platen is turned in a 45 forward or clockwise direction as viewed in Fig. 6, the rounded outer end of the arm 50 will coact with the walls of the opening 64 in the flange 54 to cause a displacement of the arm from its radial position to the extent shown, for example, in Fig. 50 7. Thus, the finger or arm 50 coacts with the stationary flange 54 during the initial portion of the rotation of the platen from its position shown in Fig. 6, to turn the rock shaft 45 about its axis and close the clamp 34 thereby securely and positively clamping the edge portion of the card 68 against the portion 35 of the platen. Inasmuch as the circular track formed by the inner surface of the flange 54 is concentric with the axis of the platen a continued rotation of the platen in a clockwise direction will hold the clamp closed and feed the card 68 forward with the platen past the feed rollers 28 and 26 to the first line writing position, such as shown in Fig. 4 and Fig. 7. If the platen is rotated still farther in a clockwise 65 direction from the position shown in Fig. 4 and Fig. 7, the rounded end of the finger or arm 50 will pass the opening 66 in the flange 54, but when the arm 50 is displaced from its radial alignment in the direction shown in Fig. 7, this direction of 70 movement of the end of the arm past the opening 66 will not afford an effective turning movement of the rock shaft 45 about its axis. In other words, when the outer end of the finger or arm 50 is trailing the rock shaft as it passes either 75 one of the openings 66 or 64, only a slight move-

ment of the rock shaft 45 about its axis will be afforded, which movement is not sufficient to afford an effective release movement of the clamp 34.

If it is desired to remove the card 68 from the clamp when the platen reaches the original position shown in Fig. 3 and Fig. 6, the platen is first rotated slightly past such position in a clockwise direction until the trailing end of the arm 50 enters the opening 64, and upon a subsequent 10 backward rotation of the platen in a counter-clockwise direction, the rounded end of the finger coacts with the walls of the opening 64 to restore the arm to its radial position, as shown in Fig. 6. This radial position of the arm operates through the rock shaft 45 to allow the clamp 34 to open under the force of the springs 40 thereby releasing the card 68.

If it is desired to feed a card backward with the platen, the platen may be rotated in either direction slightly past its position illustrated in Fig. 8 and the clamp 34 may then be opened by a slight movement in the reverse direction to effect a radial position of the arm 50 in the manner just described. Thus, the parts will be positioned as shown in Fig. 8 which permits the bottom edge portion of a card 70 to be placed between the clamp 34 and the flattened portion 35 of the platen in the same general manner as described in connection with the position of the 20 platen as shown in Fig. 6, except that in this case, the bottom portion of the card 70 coacts with a portion of the clamp 34 which extends at the opposite side of the plungers 36.

When the card 70 is inserted in the open clamp 34 as shown in Fig. 8, the platen may be rotated in a counter-clockwise direction by the finger piece 19 to close the clamp by the coaction of the finger 50 with the walls of the opening 66. The card may then be fed with the platen backward 40 past the feed rollers 26 and 28 to the first line writing position.

In writing on the card 70, the forward line spacing may be effected in the usual manner by turning the platen in a clockwise direction as viewed in Fig. 8. At the completion of the writing on the card 70, the platen may be turned in a clockwise direction to its illustrated position in Fig. 8 wherein the clamp 34 will be immediately opened due to the fact that, as the platen 50 approaches this position, the outward end of the arm 50 will be leading the rock shaft 45 and thus will coact with the walls of the opening 66 in a manner to move the arm to its radial position for releasing the clamp.

It will be clear that the control finger or arm 50 is operated in every instance a fixed distance to and from a radial position but the closing movement of the clamp 34 will vary depending on the thickness of the card which is clamped thereby. Thus the resilient connection between the arm 50 and the rock shaft 45 is provided in the present instance to allow the arm to complete its fixed extent of movement from its radial position after further movement on the rock 65 shaft has been obstructed by the engagement of the clamp with the surface of the card. This movement of the control finger or arm 50 relative to the rock shaft 45 against the force of the spring 52 will vary to a slight extent depending on the thickness of the card engaged by the clamp, but in every instance the tension of the spring 52 will provide a secure and substantially positive gripping pressure of the clamp on the card.

It will be seen that I have thus provided an improved, highly efficient and reliable card clamp for the platen of typewriting and like machines. A particular feature of the present invention is 5 the provision of operating means for the card clamp whereby rotation of the platen in either direction from a predetermined control position wherein the clamp is open, automatically operates to close the clamp and to hold the clamp in 10 an effective closed position regardless of the extent of rotation of the platen in the same direction. This automatic operating means is then arranged to open the clamp when the platen is turned in an opposite direction back to said pre- 15 determined control position.

In a specific form of the present invention shown herein, there are two such predetermined control positions of the platen wherein the clamp may be opened or closed, one of such predetermined control positions being associated with the forward feed of a card and the other being associated with the backward feed of a card. This feature of the present invention permits the clamp to be automatically closed by rotation of 20 the platen in one direction or the other from either of these two predetermined control positions and also permits the clamp to be automatically opened by turning the platen in an opposite direction back to either of such positions. 25

30 A further important feature of the present invention is in the provision of an automatic operating means for closing the clamp including a resilient means to effectively clamp cards regardless of their thickness.

35 The two openings 64 and 66 shown in the present construction for controlling the opening and closing of the clamp through the control finger 50 are provided primarily in order to open the clamp at positions which are convenient for the insertion of the top of a card in one instance and the bottom of a card in another instance, depending on whether the card is to be fed forward or backward. However, if desired, only one of such openings could be provided, and the card 40 could be inserted in the clamp at the same position thereof regardless of the direction in which it may be desired to feed the card.

45 Various other changes may be made in the construction, and certain features thereof may be omitted, without departing from my invention as it is defined in the accompanying claims.

50 What I claim as new and desire to secure by Letters Patent is:

1. In a typewriting or like machine, the combination of a carriage, a rotative platen carried thereby, a card clamp carried by the platen and engageable with a card to feed it either backward or forward with the platen as may be desired, and automatically operating means controlled by the rotation of the platen for selectively operating said clamp at a given point in such rotation depending on the direction of rotation with respect to the last previous direction of rotation thereof.

65 2. In a typewriting or like machine, the combination of a carriage, a rotative platen carried thereby, a card clamp carried by the platen and engageable with a card to feed it, and automatically operating means dependent on the direction of rotation of the platen for opening and closing said clamp at given points in the rotation of the platen, said automatically operating means comprising a control member fixed to the carriage against rotation with the platen and having a circular track with one or more open- 70

ings therein, a control finger carried by the platen and movable therewith and relatively thereto and which cooperates with said track and the opening or openings therein to be distinctively moved to a plurality of different positions relative to the platen in accordance with the rotation thereof in one direction or the other past the opening or openings, and means actuated by said control finger for controlling the opening and closing of said clamp. 10

3. In a typewriting or like machine, the combination of a carriage, a rotative platen carried thereby, a card clamp carried by the platen and engageable with a card to feed it, and automatically operating means dependent on the rotation of the platen for opening and closing said clamp at given points in the rotation of the platen, said automatically operating means comprising a control member fixed to the carriage against rotation with the platen and having a circular track with one or more openings therein, a control finger carried by the platen in cooperative relation to said track to assume one position relative to the platen while in contact with the track and to be moved into said opening or openings by rotation of the platen to thereby assume another position relative to the platen, a rock shaft carried by the platen and controlled in its rocking movement by said control finger, and means controlled by said rock shaft for controlling the opening and closing of said card clamp. 20

4. In a typewriting or like machine, the combination of a carriage, a rotative platen carried thereby, a card clamp carried by the platen and engageable with a card to feed it, and automatically operating means dependent on the rotation of the platen for opening and closing said clamp at given points in the rotation of the platen, said automatically operating means comprising a control member fixed to the carriage against rotation with the platen and having a circular track with one or more openings therein, a control finger carried by the platen in cooperative relation to said track to assume one position relative to the platen while in contact with the track and to be moved into said opening or openings by rotation of the platen to thereby assume another position relative to the platen, a rock shaft carried by the platen and controlled in its rocking movement by said control finger, a cam on said rock shaft, and means connected to said card clamp and with which said cam coacts to control the opening and closing of the card clamp. 35

5. In a typewriting or like machine, the combination of a carriage, a rotative platen carried thereby, a card clamp carried by the platen and engageable with a card to feed it, and automatically operating means dependent on the rotation of the platen for opening and closing said clamp at given points in the rotation of the platen, said automatically operating means comprising a control member fixed to the carriage against rotation with the platen and having a circular track with one or more openings therein, a control finger carried by the platen in cooperative relation to said track to assume one position relative to the platen while in contact with the track and to be moved into said opening or openings by rotation of the platen to thereby assume another position relative to the platen, a rock shaft carried by the platen and controlled in its rocking movement by said control finger, spring means that exert their force to tend to open said card clamp, a cam on said rock shaft, and means connected to said card clamp and with which said cam coacts to over- 70

come the force of said spring means and positively move the card clamp to closing or effective position.

6. In a typewriting or like machine, the combination of a carriage, a rotative platen carried thereby, a card clamp carried by the platen and engageable with a card to feed it either backward or forward with the platen as may be desired, and automatically operating means dependent on the rotation of the platen for opening and closing said clamp at given points in such rotation whether the card is being fed backward or forward with the platen, said automatically operating means comprising a control member fixed to the carriage against rotation with the platen and having a circular track with one or more openings therein, a control finger carried by the platen and movable therewith and cooperating with said track to extend radially of the platen through an opening in the track at a predetermined position of rotation of the platen and to be moved either side of said radial position depending on the direction of rotation of the platen from said predetermined position, and means actuated by movement of said control finger either side of said radial position for closing said card clamp.

7. In a typewriting or like machine, the combination of a carriage, a rotative platen carried thereby, a card clamp carried by the platen and engageable with a card to feed it either backward or forward with the platen as may be desired, and automatically operating means dependent on the rotation of the platen for opening and closing said clamp at given points in such rotation whether the card is being fed backward or forward with the platen, said automatically operating means comprising a control member fixed to the carriage against rotation with the platen and having a circular track with a plurality of openings therein, a control finger carried by the platen and movable therewith and cooperating with said track to extend radially of the platen through either of said openings in the track at predetermined positions of rotation of the platen and to be moved in either direction from said radial position depending on the direction of rotation of the platen from said predetermined positions, and means actuated by movement of said control finger to and from its radial position to control the opening and closing of said card clamp.

8. In a typewriting or like machine, the combination of a carriage, a rotative platen carried thereby, a card clamp carried by the platen and engageable with a card to feed it either backward or forward with the platen as may be desired, and automatically operating means dependent on the rotation of the platen for opening and closing said clamp at given points in such rotation whether the card is being fed backward or forward with the platen, said automatically operating means comprising a control member fixed to the carriage against rotation with the platen and having a circular track with a plurality of openings therein, a control finger carried by the platen and movable therewith and relatively thereto and which cooperates with said track and with the openings therein, a rock shaft carried by the platen and controlled in its rocking movements by said control finger, spring means that exert their force to tend to open said card clamp, a cam on said rock shaft, and means connected to said card clamp and with which said cam coacts to control the opening and closing of the card clamp, the construction and arrangement being such that when the control finger engages said track the card clamp will be held closed and when

the control finger extends through said opening the card clamp will be opened or released.

9. In a typewriting or like machine, the combination of a carriage, a rotative platen carried thereby, a card clamp carried by the platen and engageable with a card to feed it, and automatically operating means dependent on the rotation of the platen for opening and closing said clamp at given points in the rotation of the platen, said automatically operating means comprising a control member fixed to the carriage against rotation with the platen and having a circular track with one or more openings therein, a control finger carried by the platen and movable therewith and cooperating with said track to extend radially of the platen through an opening in the track at a predetermined position of rotation of the platen and to be moved either side of said radial position depending on the direction of rotation of the platen from said predetermined position, and means actuated by movement of said control finger either side of said radial position for closing said card clamp.

10. In a typewriting or like machine, the combination of a carriage, a rotative platen carried thereby, a card clamp carried by the platen and engageable with a card to feed it, and automatically operating means dependent on the rotation of the platen for opening and closing said clamp at given points in the rotation of the platen, said automatically operating means comprising a control member fixed to the carriage against rotation with the platen and having a circular track with one or more openings therein, a control finger carried by the platen and movable therewith and relatively thereto and which cooperates with said track and the opening or openings therein to be moved thereby to a plurality of different positions relative to the platen during rotation of the platen, means actuated by said control finger for controlling the opening and closing of said clamp, and spring means interposed between said card clamp and control finger to enable the card clamp to compensate for various thicknesses of cards that may be clamped in position thereby.

11. In a typewriting or like machine, the combination of a carriage, a rotative platen carried thereby, a card clamp carried by the platen and engageable with a card to feed it either backward or forward with the platen as may be desired, and automatically operating means dependent on the rotation of the platen for opening and closing said clamp at given points in such rotation whether the card is being fed backward or forward with the platen, said automatically operating means comprising a control member fixed to the carriage against rotation with the platen and having a circular track with a plurality of openings therein, a control finger carried by the platen and movable therewith and relatively thereto and which cooperates with said track and with the openings therein to be moved thereby to a plurality of different positions relative to the platen during rotation of the platen, means actuated by said control finger for controlling the opening and closing of said card clamp, and spring means interposed between said card clamp and control finger to enable the card clamp to compensate for various thicknesses of cards that may be clamped in position thereby.

12. In a typewriting or like machine, the combination of a carriage, a rotative platen carried thereby, a card clamp carried by the platen and engageable with a card to feed it either backward

or forward with the platen as may be desired, and automatically operating means dependent on the rotation of the platen for opening and closing said clamp at given points in such rotation 5
5 whether the card is being fed backward or forward with the platen, said automatically operating means comprising a control member fixed to the carriage against rotation with the platen and having a circular track with a plurality of openings therein, a control finger carried by the platen and movable therewith and relatively thereto and which cooperates with said track and with the openings therein, a rock shaft carried by the platen and controlled in its rocking movements 10
10 by said control finger, means controlled by said rock shaft for controlling the opening and closing of said card clamp, and a spring interposed between said control finger and rock shaft.

13. In a typewriting or like machine, the combination of a carriage, a rotative platen carried thereby, a card clamp carried by the platen, a spring means for opening said clamp and means for automatically controlling the opening and closing of said clamp comprising a circular track 20
20 connected to the carriage against rotation with the platen, a rock shaft carried by the platen and adapted to close said clamp against the force of said spring means, a control finger cooperating with said circular track, and resilient means 25
25 connecting said control finger with said rock shaft, said resilient means being arranged to yield only when closing movement of said clamp is positively arrested.

14. In a typewriting or like machine, the combination of a rotative platen, a card clamp carried thereby, a rock shaft extending longitudinally within the platen, a plurality of radially disposed plungers connected to said clamp, spring means coacting with said plungers, cam means on said 30
30 rock shaft coacting with said plungers to operate said clamp against the force of said spring means by rotation of said rock shaft, and means associated with said plungers for preventing lateral

flexing of said rock shaft during operation of said clamp thereby.

15. In a typewriting or like machine, the combination of a carriage, a platen rotatively mounted therein, a card clamp carried by the platen and movable relative thereto to open and closed positions, a control finger carried by the platen and movable in either direction to and from a radial position relative thereto for controlling the opening and closing of said clamp, and means secured to the carriage against rotation with the platen and coacting with said control finger to distinctively control the movements thereof in accordance with the direction of rotation of the platen. 5
10
15

16. In a typewriting or like machine, the combination of a carriage, a platen rotatively mounted therein, a card clamp carried by the platen and movable relative thereto to open and closed positions, means carried by the platen and movable relative thereto to control the opening and closing movements of said clamp, and means secured to the carriage against rotation with the platen and coacting with said means carried by the platen to close said clamp by a rotation of 20
20 the platen past a predetermined point in either one direction or the other direction depending on the last previous direction of rotation of the platen past said predetermined point. 25

17. In a typewriting or like machine, the combination of a carriage, a platen rotatively mounted therein, a card clamp carried by the platen and movable relative thereto to open and closed positions, controlling means secured to the carriage against rotation with the platen, and means carried by the platen and cooperating with said controlling means secured to the carriage to close said clamp upon rotation of the platen in one direction past a predetermined position and to hold said clamp in its closed position upon 30
30 continued rotation of the platen in the same direction past said predetermined position. 40

HENRY A. HEINRICH.

CERTIFICATE OF CORRECTION.

Patent No. 2,208,794.

July 23, 1940.

HENRY A. HEINRICH.

It is hereby certified that error appears in the printed specification of the above numbered patent requiring correction as follows: Page 6, first column, line 13, claim 12, after the word "therein" and before the comma insert -- to be moved thereby to a plurality of different positions relative to the platen during rotation of the platen--; and that the said Letters Patent should be read with this correction therein that the same may conform to the record of the case in the Patent Office.

Signed and sealed this 17th day of September, A. D. 1940.

(Seal)

Henry Van Arsdale,
Acting Commissioner of Patents.
